UNITED STATES PATENT OFFICE

ALDO CURIONI, OF LARCHMONT, NEW YORK

COMBINED AEROPLANE HELICOPTER

Application filed March 14, 1929. Serial No. 346,858.

In the past, aeroplanes having propellers, which rotate about vertical axes to enable the planes to rise as helicopters, have been very inefficient in forward flight. This is due, no doubt, to the fact that such blades of these lifting propellers as have a negative angle of incidence, in forward flight not only detract from the lift, thus tending to depress the plane, but also add to the drag and set up 10 retarding eddy currents.

The principal object of the present invention is to eliminate these disadvantages. This is accomplished by the provision of an aerofoil of such outward shape that it resembles and acts as the forward portion of a wing of a plane and at the same time is of such construction that the blades of the lifting propellers may sweep through the concave or interior portion thereof. In the form of 20 the invention illustrated below, two such lifting propellers are used, one at either side of the plane, rotating in opposite directions, those blades which extend for the moment beyond the opposite edges of the aerofoil moving forwardly. The aerofoil is located generally in the plane of rotation of the blades, forward thereof, and extends laterally between points in front of the axes of the propellers, to deflect the slip stream caused by 30 forward motion of the plane away from the rearwardly moving blades having negative angles of incidence. Portions of this wing or aerofoil, rearward of the leading edge thereof, are cut away so as not to interfere with 35 the vertical slip stream when the plane is rising or descending.

A further object of the invention resides in mounting and connecting the blades of the lifting propellers so that their angles of incidence may be varied not only to increase the lift of both propellers simultaneously, but also to increase the angle of incidence of the blades of one propeller and at the same time decrease the angle of incidence of the 45 blades of the other, so that they function as ailerons.

Another feature of the invention is the location of the lifting propellers in such relation to the wing as to supplement its action, 50 whereby a wing of comparatively short span

may be used without loss of lateral stability or net lift.

It will be appreciated at once that the combined wing and shield for the propeller effects numerous highly desirable results and greatly increases the efficiency of the plane. Not only are all the drag of the negatively inclined blades and the loss of lift therefrom eliminated, but by far the greater part of the lift caused by the ordinary wing is retained without, at the same time, any great interference with the helicopter action of the propellers.

These and other objects and advantages will appear from the following detailed description of a preferred embodiment of the present invention, reference being had to the accompanying drawings, wherein:

Figure 1 is a plan view of the top of the combined aeroplane and helicopter.

Figure 2 is a front elevation thereof.

Figure 3 is a side elevation.

Figure 4 is a detail view showing the lower wing and vertical strut in section, and the mechanism for controlling the blades of the 75 propellers.

Figure 5 is a detail view taken on the line 5-5 of Figure 4, looking in the direction of the arrows.

Figure 6 is an enlarged section of the upper aerofoil or wing, showing the propeller blades and air currents.

In Figures 1, 2 and 3 there is shown a combined aeroplane and helicopter having a fuselage *a*, a lower wing *b*, landing gear *c*, tail-skid *c'*, horizontal and vertical tail surfaces *d* and *d'*, respectively, motor *g*, propeller shaft *g'*, and propeller *g''*. These may all be more or less as usual in an ordinary aeroplane.

The propellers which effect the helicopter action comprise blades *f* swivelled on radial arms *f'* which are fixed to hubs *f''*. These hubs may be integral with vertical shafts *f''*, as shown in Figure 4. These shafts are 95 mounted in the vertical struts *f''*, which are supported on the lower wing *b*. Keyed to the shafts are pulleys *f''*, which are driven from the motor *m* through worm *m'*, wheels *m''*, and belts *m'''*.

For varying the angles of incidence of the blades, arms h , rigidly attached to the blades at one side of the arms f' , are connected by eyes h' to links h^2 , which are connected in turn to yokes h^3 swivelled on shafts h^5 . Shafts h^5 are journaled within shafts f^4 and are connected through their rounded ends h^6 to forked arms h' which are secured rigidly to shafts h^8 . Shafts h^8 are pivoted in supports h^9 and h^{10} , and have arms h^{11} secured to their inner ends. Links h^{12} connect these last named arms to a yoke h^{13} which is pivoted on stick h^{14} to swing thereabout, said post being mounted at h^{15} to swing in a vertical plane. By pulling stick h^{14} rearwardly the angle of incidence of all the blades is increased, while by rocking the yoke h^{13} the plane is caused to bank.

The wing or aerofoil which serves as the shield for the rearwardly moving blades of the lifting propellers is shown at e with its leading edge at e' . The upper and lower surfaces of this aerofoil, e^2 and e^3 , respectively, extend rearwardly over and under the tips of the blades and to such further extent as is desirable for purposes of lift and as may be necessary from constructional standpoints. The leading edge of the shield is located forwardly of the tips of those blades which are just starting to move rearwardly. Since it is desirable that a single aerofoil shield all the rearwardly moving blades, the propellers are caused to rotate in opposite directions as indicated by the arrows in Figure 1, and the aerofoil is extended across the path of said rearwardly moving blades, while the forwardly moving blades are outside of the shield. The aerofoil is hollow between the upper and lower portions so that parts of the blades may sweep therebetween. These portions are cut away as at e^4 and e^5 , respectively, to form passageway for whatever slip-stream is caused by rotation of the blades f . In Figure 1, a particular form of the cutaway portions is illustrated and is best described by reference to said figure. However, it is to be understood that the invention is not confined to any special form or shape of these parts. The characteristics of a given aerofoil are determinable, so that given the basic idea of the present invention, one will be able to construct various different shapes of wing for the present purposes.

In Figure 6, there is shown a wing section e' , e^2 , e^3 , a feature of the present invention, and in dotted lines e^6 the usual wing section. The general flow of air past applicant's aerofoil is suggested by the lines x , y and z . Propeller blades f are also indicated in dotted lines. This figure is merely illustrative, and applicant does not wish to be held to any particular theories of aerodynamics.

In the arrangement shown in Figure 1 there is one motor for the lifting propellers and

one for the tractor propeller. It will be appreciated that these may be coupled to operate together in any suitable manner, or only one motor may, in some cases, be used. In the embodiment illustrated, when the lifting propellers are stopped, or moving slowly, after the plane has gained altitude, the outer blades of said propellers still contribute to the lift, due to their positive angle of incidence, but the whole forward motion may be supplied by the tractor propeller. Due to the lift of the former, the wing camber or area may be correspondingly decreased.

It will thus be seen that applicant has provided means whereby a helicopter type plane may operate efficiently in forward flight. Such means consist, briefly, of a wing which is also a shield for certain blades of the lifting propeller. Hence the invention is not to be limited by the shape of the aerofoil, nor to a biplane, nor in any other way, save as defined by the appended claims.

I claim as my invention:

1. In an aeroplane, in combination with a plurality of propellers mounted for rotation about normally vertical axes, an aerofoil shield between the propellers, and aerofoil portions forward of those propeller blades which have a negative angle of incidence.

2. In an aeroplane, a substantial horizontal aerofoil, a plurality of propeller shafts, propeller blades mounted thereon and lying in a normally horizontal plane, and means to mount the shafts so that those blades which have a negative angle of incidence lie in the general plane of the aerofoil and rearwardly thereof, whereby the aerofoil acts as a shield for the last named blades in forward flight.

3. In an aeroplane, an aerofoil having a leading edge and upper and lower surfaces extending rearwardly thereof to form a hollow space between the surfaces, a propeller shaft, propeller blades mounted thereon and lying in a normally horizontal plane, and means to mount the shaft so that the tips of some of the blades having a negative angle of incidence lie in the hollow space.

4. In an aeroplane, an aerofoil having a leading edge and upper and lower surfaces extending rearwardly thereof to form a hollow space between the surfaces, a propeller shaft, propeller blades mounted thereon and lying in a normally horizontal plane, and means to mount the shaft rearwardly of the end of the aerofoil so that the tips of some of the blades having a negative angle of incidence lie in the hollow space.

5. In an aeroplane, a propeller shaft, propeller blades mounted thereon and lying in a normally horizontal plane, an aerofoil having a leading edge and upper and lower surfaces extending rearwardly thereof to form a hollow space between the surfaces, extending laterally the length of a blade, and formed with openings in said surfaces rearward of

the leading edge, and means to mount the shaft rearwardly of the end of the aerofoil so that the tips of some of the blades having a negative angle of incidence lie in the hollow space.

5 6. In an aeroplane, a substantially horizontal aerofoil, a plurality of propellers whose blades lie in the plane of the aerofoil and rearwardly of the leading edge thereof, 10 and means to mount the propellers at either side of the aeroplane, whereby the aerofoil deflects the slip stream in forward flight from said blades.

7. In an aeroplane, a substantially horizontal aerofoil, a plurality of propellers whose blades lie in the plane of the aerofoil and rearwardly of the leading edge thereof, 15 and means to mount the propellers at either side of the aeroplane for rotation about normally vertical axes, the axes being located 20 approximately in line with the respective lateral edges of the aerofoil.

8. In an aeroplane, a substantially horizontal aerofoil having a leading edge and 25 upper and lower surfaces extending rearwardly thereof to form a hollow space between the surfaces, a plurality of propellers whose blades lie in the plane of the aerofoil, and means to mount the propellers at either 30 side of the aeroplane so that the tips of some of the blades having a negative angle of incidence lie in the hollow space.

9. In an aeroplane, a substantially horizontal aerofoil having a leading edge and 35 upper and lower surfaces extending rearwardly thereof to form a hollow space between the surfaces, a plurality of propellers whose blades lie in the plane of the aerofoil, and means to mount the propellers at either 40 side of the aeroplane so that the propellers rotate about normally vertical axes, the axes being located approximately in line with the respective lateral edges of the aerofoil and at such distance from the leading edge there- 45 of that the tips of some of the blades having a negative angle of incidence lie in the hollow space.

10. In an aeroplane, a substantially horizontal aerofoil, a plurality of propellers 50 whose blades lie in the plane of the aerofoil and rearwardly of the leading edge thereof, and means to mount the propellers at either side of the aeroplane, for rotation about normally vertical axes, the axes being located 55 approximately in line with the respective lateral edges of the aerofoil and the blades for the moment laterally outward of the aerofoil adding their effective lift to that of the aerofoil in forward flight.

60 11. In an aeroplane, an aerofoil shield, a rotatable member at either end and projecting beyond the sides thereof, and means to mount the member to destroy a portion of the turbulence back of the shield.

65 12. In an aeroplane, a pair of rotatable

members, and an aerofoil shield lying generally in the plane of the rotatable members, a portion of the shield extending forwardly of the members to substantially the fore and aft planes extending through the rotating 70 axis of the members.

13. In combination with a standard aerofoil having the property of lifting a plane against suitable wind pressure, rotating members carried by the plane, and cut away portions adjacent the rear ends of the aerofoils to position the leading ends of the aerofoil over a portion of the frontal profile of the rotating members.

This specification signed this 9th day of 80 March, A. D. 1929.
